FUSE

William O. Schultz, South Milwaukee, Wis., assignor to Line Material Company, Milwaukee, Wis., a corporation of Delaware

Application April 30, 1943, Serial No. 485,099

10 Claims. (Cl. 200—127)

This invention relates to electric fuses of the expulsion type and has to do, in part, with improvements in fuse-links and, in part, with a novel fuse cartridge and fuse-link combination.

Two distinct objects are achieved. One of these is the effectuation, in a very simple way, of a closure for the discharge end of the fuse cartridge whereby to exclude insects which sometimes import mud and other substances in such quantities as to impede operation of the fuse; and the other object is to devise a fuse-link which requires no anchorage outside the fuse cartridge and which, therefore, is particularly well adapted for use in bayonet type fuses.

In the preferred construction herein described, the fuse-link comprises a fusible section and a retracting spring which functions to separate the terminals of the fusible section when a blowout occurs. The fuse-link is designed to be inserted in the cartridge at the discharge end of the latter and it has a conically shaped terminal which makes good electrical contact with the ferrule attached to the lower end of the cartridge and serves as a closure member to exclude insects etc. from the cartridge bore without interfering with normal operation of the fuse. At the same time the conically shaped contact terminal constitutes an anchorage member for the lower end of the fuse-link.

A conventional fuse-link such as commonly employed in expulsion fuses includes, as one terminal, a flexible conductive leader which is utilized to pull the fuse-link into the cartridge and is then fastened, usually under tension, to a binding post exterior of the cartridge. But that kind of fuse-link cannot conveniently be adapted for use in bayonet type fuses unless modified in a way which renders it somewhat complicated to install. Therefore, in order to facilitate installation of the link while eliminating the usual flexible leader, the subject fuse-link, in its preferred form, is provided with a telescopically extensible or equivalent terminal member which, when extended, renders the over-all length of the unstretched fuse-link sufficient to reach all the way through and beyond the cartridge bore so that the extruded end can readily be grasped by the installer—whereupon the fuse-link is stretched by the installer to tension the retracting spring, and the upper terminal of the link is anchored in a manner effective to retain the link under tension while securing it in place in the cartridge.

My new fuse-link is characterized by sim-

plicity of construction, economy of manufacture, and ease of installation and replacement.

In the drawing which accompanies this specification:

5 Fig. 1 is a vertical sectional view of a fuse cartridge with a fuse-link in course of installation;

10 Fig. 2 shows the same assemblage as Fig. 1 after the fuse-link installation has been completed; and

Fig. 3 depicts a modification.

The fuse cartridge, which includes tube 1 together with upper ferrule 2 and lower ferrule 3, is a component part of an entire expulsion fuse

15 structure of the bayonet type shown in the co-pending application of Chester W. Brown, Serial No. 466,512, filed November 21, 1942, but obviously may be adapted by slight modification for use in other styles of expulsion fuses employing functionally similar cartridges. Therefore, I do not wish it to be supposed that the utility of my invention is limited to bayonet type fuses.

20 Tube 1 may be of horn fiber, but usually is composed of "Bakelite" lined with horn fiber, which latter has the capacity to emit arc-extinguishing gas or vapor when heated by the arc which strikes when the fuse-link blows in response to a heavy over-load or short circuit.

25 30 Contact and retainer member 4 and the balls 5 together with attaching screws 6 constitute portions of the locking mechanism which characterizes the bayonet fuse of the aforementioned Brown application wherein they are fully described. Those parts bear no indispensable relation to the present invention and for that reason they will not be further described herein.

35 The upper end of ferrule 2 is threaded externally at 2a to engage a complementary internal thread in a cap member, not shown, which forms a part of the fuse housing.

40 Electrical connection is effected with the upper end of the cartridge and enclosed fuse-link by way of contact springs 4, and with the lower end of the cartridge and fuse-link via ferrule 3.

45 The fuse-link extending through the bore of the cartridge normally interconnects ferrules 2 and 3, thus completing the circuit in which the fuse is included.

50 The major components of the fuse-link are: an upper terminal member 1, retracting spring 8, flexible conductor 9, fusible section 10 and lower terminal 11.

55 Fusible section 10 is composed of a fuse wire

12 and strain wire 13 attached at their upper ends to a stud 14 which is detachably threaded into a coupling member 15. The lower ends of the fuse and strain wires are attached to lower terminal 11—which latter comprises a frusto-conical lower terminus 11a and a central stem 11b. A metal sleeve 16 attached to stud 14 serves as a securing medium for a fiber tube 17 which depends therefrom and encases the fuse and strain wires. The lower end of tube 17 is unattached. It will be evident that upon blowing of the fuse, stud 14 together with tube 17 becomes free to move upwardly under the impetus of spring 8, while terminal 11 becomes free to drop out or to be blown out by the pressure generated within the cartridge.

The lower end of retracting spring 8 is attached to coupling member 15 while its upper end is attached to upper terminal member 7. Said spring is under tension when the fuse-link is in place, as per Fig. 2, and is thus operative quickly to elevate parts 14, 15, 16, and 17 when the fuse blows.

In order to avoid a heavy current flow through the retracting spring, there is provided in shunt thereto the flexible conductor 9. The latter is so flexible that it readily collapses as the spring contracts.

Obviously, the fuse-link must be inserted in the cartridge from the lower end thereof; and it is not convenient to use a flexible leader as the upper terminal of the fuse-link because of difficulties involved in effecting an anchorage and at the same time keeping the upper end of the cartridge sealed, while avoiding complexity and ensuring against the consequences of negligence on the part of linemen in making fuse-link replacements. So, for the purpose of avoiding the use of a flexible leader as the upper terminal, while at the same time making it easy to effect a replacement installation wherein the upper terminal connection will not become dislodged, even though the lineman may be careless about the quality of his workmanship, I have devised the upper fuse-link terminal 7 and complementary cartridge construction—which will now be described and explained.

It should first be pointed out that when the fuse-link is free the retracting spring 8 is contracted lengthwise and devoid of tension, wherefore, in the absence of special provision to the contrary, the unstretched fuse-link would be shorter than the cartridge, and it would for that reason be quite difficult to tension the spring and effect an installation of the link. In the conventional fuse-link the flexible leader meets that problem by being long enough to reach through the cartridge bore—being, in most cases, cut to length after installation. The design of terminal 7 meets that problem without entailing a cutting off operation and thus preserves the terminal for re-use in conjunction with a replacement fusible section following a blowout.

Upper terminal 7 comprises an elongate tubular member 18 having an external radially projecting flange 18a at its upper end and is threaded at its lower end for attachment to retracting spring 8.

The upper end of tubular member 18 is threaded internally to receive a plug 19 which is bored coaxially with member 18 to provide a sliding fit for a rod 20 having a lower head 21 disposed within the bore of member 18 and slidable axially therein. The upper end of rod 20 is provided with a head 22 designed to serve as a knob. It will

be clear that rod 20 and member 18 are telescopically interconnected—that fact being self-evident from a comparison of Figs. 1 and 2. Also, it will be apparent that plug 19 operates as a stop to limit the outward movement of rod 20 by engaging lower head 21.

Flange 18a is designed to rest on a shoulder 2b (see Fig. 2) formed internally of ferrule 2. Thus, shoulder 2b constitutes an abutment co-operating with ferrule 3, which latter functions as a complementary abutment to resist the tension of spring 8.

Flange 18a has an external diameter less than that of the cartridge bore and, therefore, it will readily pass through the cartridge. But, the flange width, radially, is sufficiently generous to effect a good and secure seat upon shoulder 2b—the inter-contact subtending a large arcuate portion of the shoulder.

20 A thumbscrew 22' ensures against unintended dislodgment of flange 18a from shoulder 2b, but I have found that it is practically impossible for said flange to become dislodged, except by intention, irrespective of thumbscrew 22'. In other words, thumbscrew 22' is largely superfluous, but it serves to make doubly sure that the fuse-link will remain in place indefinitely, provided there is no blowout.

Installation of the fuse-link is accomplished 30 by inverting both the cartridge and fuse-link end for end and inserting the fuse-link. By so doing, rod 20 is caused by gravity to slide outwardly of tube 18 to its most extended position—which renders the unstretched fuse-link longer than 35 the cartridge and enables the service man to grasp knob 22. The fuse-link is thereupon stretched by pulling on knob 22, to approximately the extent exhibited in Fig. 1 or, at least, until flange 18a can be seated on shoulder 2b—as depicted in Fig. 2. Thereafter thumbscrew 22' is turned to engage the side of member 18. But, if the serviceman neglects to adjust thumbscrew 22', no harm is likely to result.

Rod 20 may appropriately be described as a 45 "fishing rod" since its sole function is to enable the service man to "fish" the upper terminal out of the cartridge bore sufficiently to enable it to be anchored.

When the loaded cartridge is turned right side 50 up, rod 20 drops down into the bore of member 18 as illustrated in Fig. 2.

It will be observed that the lower end of the cartridge is closed against the entry of insects. The upper end likewise is closed when the cartridge is in place.

In Fig. 3 there is illustrated a modification 60 of the upper end construction where, instead of a telescoped "fishing rod," there is substituted a detachable rod 23. Here the upper fuse-link terminal member corresponding to member 18 of Figs. 1 and 2 is identified by reference numeral 24 and has a flange 24a corresponding to flange 18a of Figs. 1 and 2. The lower end of rod 23 is screwed into member 24 for the purpose of adding length to the fuse-link, and after the fuse-link has been installed rod 23 is unscrewed and removed. Obviously the construction of Fig. 3 performs the same function as that of Figs. 1 and 2, but it has the disadvantage that rod 23 is not 65 a permanent part of the fuse-link.

What is claimed is:

1. A fuse link assembly comprising: a pair of spaced terminals, a fusible section and a tension spring in series interconnecting said terminals, 75 said spring being yieldable to permit elongation

of the fuse-link and effective, when tensioned, to bias said fusible section, the terminal connected with said spring including a tubular member having a contact engaging portion and a rod telescoped with said tubular member, said rod being freely and independently movable telescopically relatively to said tubular member and co-linearly with the fuse-link, and stop means for preventing disengagement of said rod from said tubular member.

2. A fuse-link assembly comprising: a pair of spaced terminals, a fusible section interconnecting said terminals, one of said terminals being extensible and contractible co-linearly with the fuse-link and including a tubular member having a contact engaging portion and a rod telescopically engaged with and freely movable relative to said tubular member.

3. A fuse-link assembly comprising: a pair of spaced terminals, a fusible section interconnecting said terminals, one of said terminals being extensible and contractible co-linearly with the fuse-link and including a tubular member having a radially extending external protuberance operative as an anchoring means for one end of the fuse-link, and a rod telescopically engaged with and freely movable relative to said tubular member.

4. A fuse-link assembly comprising: a pair of spaced terminals, a fusible section interconnecting said terminals, one of said terminals being extensible and contractible co-linearly with the fuse-link and including a tubular member having an external flange operative as an anchoring means for one end of the fuse-link, and a rod telescopically engaged with and freely movable relative to said tubular member.

5. In combination: a fuse cartridge having a bore extending lengthwise therethrough, said cartridge having an internal shoulder near one end, and a fuse-link in said cartridge, said fuse-link comprising a pair of terminals anchored to opposite ends of said cartridge, and a fusible section interconnecting said terminals, one of said terminals having an external protuberance effecting an anchoring engagement with said shoulder, and a fishing rod telescopically connected with and freely movable relative to said last-mentioned terminal, the over-all length of the fuse-link being extensible by moving said rod outwardly of said last-mentioned terminal.

6. In combination: a tubular fuse cartridge and a fuse-link therein, said fuse-link comprising a pair of spaced terminals, a fusible section and a tension spring in series interconnecting said terminals, said fuse-link being extensible lengthwise by stressing said spring, one of said terminals including a pair of overlapping members which are freely and independently relatively movable lengthwise of the fuse-link whereby the length of said terminal can be temporarily extended to facilitate installing the fuse-link in the cartridge, the over-all length of the fuse-link with said spring unstretched and said extensible terminal unextended being less than that of said cartridge, the over-all length of the unstretched fuse-link with said extensible terminal fully extended being greater than that of said cartridge.

7. In combination: a tubular fuse cartridge and a fuse-link therein, said fuse-link comprising a pair of spaced terminals, a fusible section and a tension spring in series interconnecting said terminals, said fuse-link being extensible lengthwise by stressing said spring, the terminal connected with said spring including a tube having a

contact engaging portion and rod telescopically and freely movable independently and lengthwise of said tube whereby the length of said terminal can be temporarily extended to facilitate installing the fuse-link in the cartridge, the over-all length of the fuse-link with said spring unstretched and said extensible terminal unextended being less than that of said cartridge, the over-all length of the unstretched fuse-link with said extensible terminal fully extended being greater than that of said cartridge.

8. In combination: a tubular fuse cartridge and a fuse-link therein, said fuse-link comprising a pair of spaced terminals, a fusible section and a tension spring in series interconnecting said terminals, said fuse-link being extensible lengthwise by stressing said spring, one of said terminals including a tube having a terminal engaging portion and rod telescopically movable lengthwise of and relative to said tube whereby the length of said terminal can be temporarily extended to facilitate installing the fuse-link in the cartridge, the other of said terminals being conically shaped and operative as a closure for the discharge end of said cartridge, the over-all length of the fuse-link with said spring unstretched and said extensible terminal unextended being less than that of said cartridge, the over-all length of the unstretched fuse-link with said extensible terminal fully extended being greater than that of said cartridge.

9. In combination: a tubular fuse cartridge having conductive abutment means at each end, one of said abutment means being a shoulder within the bore of the cartridge, and a fuse-link within said cartridge and tensioned between said abutment means, said fuse-link comprising a pair of spaced terminals engaging said abutment means individually, a fusible section and a tension spring in series interconnecting said terminals, said fuse-link being extensible lengthwise by stressing said spring, one of said terminals including a tube and rod telescoped together and relatively movable lengthwise of the fuse-link whereby the length of said terminal can be temporarily extended to facilitate installing the fuse-link in the cartridge, said tube having an external radial protuberance seated on said shoulder and serving to anchor said tube thereto, the other of said terminals being operative as a closure for the discharge end of said cartridge, the over-all length of the fuse-link with said spring unstretched and said extensible terminal unextended being less than that of said cartridge, the over-all length of the unstretched fuse-link with said extensible terminal fully extended being greater than that of said cartridge.

10. In combination: a tubular fuse cartridge and a fuse-link therein, said fuse-link comprising a pair of spaced terminals, a fusible section and a tension spring in series interconnecting said terminals, said fuse-link being extensible lengthwise by stressing said spring, one of said terminals comprising a sleeve, a rod freely slidable in said sleeve and means within said sleeve preventing complete disengagement of said rod from said sleeve, said sleeve and rod being operative to extend the length of said fuse-link whereby the insertion of said fuse-link in said fuse cartridge is facilitated, said rod being nested in said sleeve when said fuse-link is mounted in said cartridge.
